(57) **CLAIM**

The ornamental design for an electrical connector as shown and described.

DESCRIPTION

FIG. 1 is a front view of an electrical connector of my design.

FIG. 2 is a back view of the electrical connector of FIG. 1. FIG. 3 is a right side view of the electrical connector of FIG. 1.

FIG. 4 is a left side view of the electrical connector of FIG. 1.

FIG. 5 is a top view of the electrical connector of FIG. 1. FIG. 6 is a bottom view of the electrical connector of FIG. 1.

FIG. 7 is a perspective view of the electrical connector of FIG. 1.

FIG. 8 is a cross-sectional view along line 8-8 as shown in FIG. 1.

FIG. 9 is a cross-sectional view along line 9-9 as shown FIG. 1.

FIG. 10 is a cross-sectional view along line 10-10 as shown in FIG. 1.

FIG. 11 is a cross-sectional view along line 11-11 as shown in FIG. 1; and,

FIG. 12 is a cross-sectional view along line 12-12 as shown in FIG. 3.

The dash-dash broken lines shown in the figures are included for the purpose of illustrating portions of the electrical connector and form no part of the claimed design. The dash-dot-dash broken lines represent the bounds of the claimed design and form no part thereof.
